US00D577006S

(12) **United States Design Patent**
Amai

(10) **Patent No.:** **US D577,006 S**
(45) **Date of Patent:** **** Sep. 16, 2008**

(54) **LOUDSPEAKER**

(75) Inventor: **Masatoshi Amai**, Meguro-ku (JP)

(73) Assignee: **Pioneer Kabushiki Kaisha**, Tokyo (JP)

(**) Term: **14 Years**

(21) Appl. No.: **29/290,493**

(22) Filed: **Dec. 11, 2007**

(30) **Foreign Application Priority Data**

Jun. 22, 2007 (JP) 2007-016729

(51) **LOC (8) Cl.** **14-01**

(52) **U.S. Cl.** **D14/216**

(58) **Field of Classification Search** D14/204, D14/209-216, 219-220, 222; 181/143-144, 181/147-148, 150, 157, 198-199, 151, 153; 381/300-302, 306, 333, 345, 361-364, 386-388, 381/332, 336

See application file for complete search history.
